UNITED STATES PATENT OFFICE.

KIYOSHI NAGAI, OF SAN FRANCISCO, CALIFORNIA.

SANITARY FINE-TOOTH COMB.

Application filed March 9, 1926. Serial No. 93,363.

This invention relates to a device for cleaning the teeth of a fine tooth comb, and its object is to provide a device which is capable of indefinite use, and which does not have certain defects present in the ordinary metal comb cleaners.

It will be understood by those skilled in the art that fine tooth combs are provided with a series of exceedingly fine teeth, the distances between each of the several teeth being so small that it is very difficult to cut slots in a sheet of metal narrow enough to leave a sufficiently solid tooth to be of any effect in cleaning the comb so that the only kind of metal that can be used for that purpose satisfactorily is a piece of wire which is usually drawn to give it the necessary strength, and in the present instance a plurality of wires are used so that there is one wire for each space between the several teeth in the comb, and the wire is suitably supported so that it is used in tension and not as the teeth of the comb are used, so that it is adequate to remove any material that may adhere to the teeth.

An embodiment of the invention is shown in the accompanying drawings in which the same reference numeral is applied to the same portion throughout the several figures of the drawings, and of which there may be modifications:

Figure 1 is a longitudinal sectional view of one form of the comb,

Figure 2 is a transverse sectional view of the said comb,

Figure 3 is an illustration of the method of producing the cleaning wires used in the form of comb shown in Figure 1,

Figure 4 is a side elevation of a cheaper construction, and

Figure 5 is a transverse sectional view of the comb shown in Figure 4.

Figure 6 is a perspective view of a comb having teeth on only one side thereof showing the cleaning wires substantially the same as those used in Figure 1.

The comb back is indicated at 1, and it has the teeth 2 common to all fine teeth combs. This comb is slidable in a flat rectangular case 3, which is open to provide a slot for the projection of the teeth from the case. The back is provided with a slot at 4

through which a pin 5 passes to enable the lever 6 to raise the comb enough to clean the teeth of any adhering matter.

The lever 6 is pivoted to the top of the case at 7 and has a handle 8 which lies down flat on the top of the case when the comb is ready to be used. In order to provide for convenience in handling, the top of the casing is provided with two small mouldings 9 and 10. A stop 8' prevents the lever 8 from being lifted so high as to disengage the teeth 2 from the wires.

The cleaning device consists of a series of wires 11, which are secured to small plates 12 and 13 on opposite sides of the lower portion of the comb casing. These wires are all arranged in a series of bars as illustrated in Figure 3 at 12 and 13, there being enough of the wires to completely cover the bars and they are arranged so that one wire passes between each pair of comb teeth. These strips carrying the wires are then secured to the comb casing by soldering or otherwise, so that the wire passes through the spaces between the comb teeth and the comb is lifted up and down from time to time to clean it with the lever 8.

In the form of the invention shown in Figures 4 and 5 there are two flat plates 20—21 which plates are wound with a plurality of wires 22 which pass through the spaces between the teeth of the comb and between edges of the ordinary fine tooth comb, said teeth being indicated at 23 and 24.

The comb is long enough so that it projects from the casing formed by the two plates 20 and 21, and said plates have knobs 25 and 26 thereon to aid in shifting the casing with respect to the comb.

In Figure 6 there is shown a comb having teeth 30, the comb back having the projecting notched ends 31 and 32 for operating it.

The comb cover consists of a strip of sheet metal folded upon itself to form two portions 33 and 34 to each of which wire carrying strips 12 and 13 may be secured the same as is shown in Figures 2 and 3. The wires 11 then extend across the edges of the two plates 33 and 34 and between the teeth 30 of the comb.

Having thus described my invention, what

I desire to secure by Letters Patent of the United States is as follows, but modifications may be made in carrying out the invention as shown in the drawings and in the above particularly described form thereof, within the purview of the annexed claim:

A comb cleaner comprising a frame in which a comb is adapted to slide, said frame being open on one edge to allow the teeth of said comb to project outside of said frame, a bar on each side of said frame adjacent and

parallel with said opening, and wires extending from one bar to the other across said opening, and adapted to pass between the teeth of said comb, and means of projecting said comb with the teeth thereof outside of said frame to the limit of said cross wires. 15

In testimony whereof I have hereunto set my hand this 27th day of February A. D., 1926.

KIYOSHI NAGAI.
